EDWIN L. MILLER, OF KANSAS CITY, MISSOURI.

GAS-GENERATING OIL-BURNER.

1,307,206.

Specification of Letters Patent. Patented June 17, 1919.

Application filed January 24, 1919. Serial No. 272,928.

To all whom it may concern:

Be it known that I, EDWIN L. MILLER, a citizen of the United States, residing at Kansas City, in the county of Jackson and 5 State of Missouri, have invented a new and useful Gas-Generating Oil-Burner, of which the following is a specification.

My invention relates to gas generating oil burners and particularly to a device of this 10 character which is used in heating furnaces and stoves.

The objects of my invention are, first, to provide a simple and inexpensive gas generating oil burner device which may be readily 15 installed in furnaces and stoves, second, to provide the device with a retort having facility for self cleaning, third, to provide the device with a mixer having facility for receiving and mixing the gas from the retort with air and provided with an outlet 20 for the mixture which is adapted for a torch flame, fourth, to provide a housing for the mixer and having a series of vent orifices for venting the gas mixture to produce a 25 blue flame and, fifth, to provide a base for the device having facility for conserving the oil wasted through the retort.

I attain these objects and other advantages by means of the construction and combination of parts illustrated in the accompanying drawing in which—Figure 1, is a vertical section through the device constructed in accordance with my invention; Fig. 2, is a top plan view of the housing burner, a part of my invention; Fig. 4, is a top plan view of a modified form of the housing burner; and Fig. 3, is a top plan view of the base plate, and showing the basin for receiving wasted oil and the convexed 40 boss therein for receiving and supporting the housing burner and for spreading oil and flame. Fig. 5, is an elevation, partly sectioned, of the device with housing removed and ready to produce a torch flame.

45 The horizontally disposed oblong base plate 1, is provided on its upper side with a vertical flange 2, which extends longitudinally of the plate in the form of an ellipse, thereby forming an elliptical shaped basin 3 within the limits of the flange and substantially coextensive with the plate. A boss 4, is formed up centrally of the basin 3, and extends thereabove a distance adapted for entering the lower end of a housing hereinafter described, to hold the same in vertical position. The upper end of the boss is

convexed throughout, and the convexed portion is provided with circular openings 5, which are adapted for receiving the lower terminals of a substantially inverted U-shaped pipe 6, having a circular opening 7, in its upper arch communicating with the interior of the pipe and a similar opening 8, in its lower arch communicating with the pipe and registering with the opening 7. 60 Annular flanges 9, are formed circumferentially of the lower portions of the terminals of the pipe and are adapted to bear on the convexed side of the boss 4, and support the pipe in vertical position. The peculiar 65 form of the pipe 6, combined with the openings 7 and 8, in the bend thereof, forms a specially contrived gas mixer 10, as will hereinafter be explained. A housing and burner member 11, comprising a circular 70 and vertically extending foot portion 12, which is formed integral with a horizontally disposed elongated oval and elliptical body portion 13, having a convexed bead 14, extending around its peripheral edge and 75 provided with vents or orifices 15, which communicate with the interior of the body portion, is placed to stand vertical in the basin 3, entirely housing the mixer 10, the 80 boss 4 being entered in the foot portion 12, 85 to hold the housing stable and in place. Orifices 16, are formed circumferentially of the foot portion 12, at intervals and located at points adapted for the passage there- 90 through of wasted oil from the convexed side of the boss 4. Slots 17, are formed in the lower edges of the foot portion 12, at intervals, for the passage of oil into the basin 3. A boss 18, is formed centrally on the upper side of the body portion 13, of the 95 housing burner member and provided with a hole 19, which registers with the opening 7, in the mixer, when the parts are operatively assembled. A retort 20, comprising an elliptical hollow member, is provided 100 centrally on its lower side with a boss 21 having a cored extension 22, and is mounted on the upper side of the housing member, the extension 22, being entered in the hole 19, and extending therethrough and through 105 the intervening space in the housing and into and penetrating the opening 7, in the mixer, to adjacent the interior of the pipe 6, the boss 21, meanwhile bearing upon the boss 18, and thereby the gas generated in the 110 retort is delivered to the mixer and the retort held in place. An oil supply pipe 23,

is connected with the one end of the retort, rising vertically in parallelism with the device and at a distance therefrom to prevent injury and to be acted on by the flame. The 5 housing member may be turned while in place, to assume any desired position relative to the retort, so that the latter may be subjected to the flames in more or less degree.

To use the device, for instance, in a heating furnace, the base plate 1, is passed 10 through the feed door of the furnace and laid flat upon the grate bars, the space about the plate being filled by asbestos or other suitable filling material, so that air shall be 15 excluded from the device, excepting the air which shall flow in through the pipe 6, the mouths of which are disposed to receive air from the ash pit. The U-shaped mixer member is then mounted on the base in vertical 20 position, the terminal ends of the pipe being entered in the openings 5, in the boss 4, the flanges 9, resting on the convexed side of the boss. If it is desired to use the housing 25 burner member 11, to obtain a series of blue flames projected toward the sides of the fire pot, the member mentioned is placed to stand on the base plate, in the basin, the boss 4, being entered into the foot portion of the housing. The retort 20, is then 30 mounted on the upper side of the body portion of the housing or burner, the extension 22, being entered in the hole 19, in the boss 18. The extension 22, extends completely 35 through the upper wall of the housing member and is entered into the opening 7, in the upper arch of the pipe 6, terminating at a suitable point therein inwardly of the interior of the pipe. The pipe 6, and the extension 22, are provided with capacity for 40 conducting air and gas respectively, in volume suitable for obtaining the proper mixture to produce a combustible gas. The oil supply pipe 23, is then connected with the end of the retort and the oil permitted to 45 flow into the retort in any suitable regulated quantity. The retort being cold, the oil will gravitate from the retort through the extension 22, and through the opening or discharge outlet 8, in the lower arch of the pipe 50 6, into the foot portion of the housing member and upon the convexed side of the boss 4, and pass therefrom through orifices 16 and 17, into the basin 3, where the oil is ignited. The burning oil in the basin will effect a 55 heating of the device to a degree sufficient to volatilize the oil, first converting the oil within the foot portion of the housing into a gas which is mixed with air admitted through the outlet 8, from pipe 6, the gas being vented 60 at the vents 15, and ignited by flame from the basin, the gas flames thereafter completing the heating of the retort to convert the oil therein into gas. When gas is generated in the retort it is forced to flow 65 through the extension 22, and is projected

across the interior of the pipe 6, through and out of the outlet 8. In its transit across the pipe the gas mixes with the air in the pipe and passes into the housing burner member and is vented therefrom at the orifices 15, where it is ignited and burns, in the well known manner. The multiplicity of small orifices 15, in the periphery of the burner member operates to effect complete combustion of the gas permitted to flow 75 therefrom and, the mixture of gas and air being in proper proportion the vented gas will burn with a blue flame and surmounted by a purplish tip and produce intense heat. When the retort is generating gas the flow 80 of oil to the basin 3, is suspended and the initial priming flame in the basin is extinguished or dies because of the lack of supply of oil.

If it is desired to use the device for producing a torch flame the burner member is removed and the priming practice mentioned is repeated. In this case the oil will burn in the basin and around the pipe 6, the flames acting directly upon the retort, thereby starting the generating of gas in the retort with promptness. The gas from the retort will flow and mix with air as before mentioned, but it will ignite below the outlet 8, at and about the convexed side of the 95 boss 4, which in this case operates as a spreader, the flames consequently being present everywhere within the limits of the fire pot of the furnace. The expansive force of the gas operates to effect a rapid flow of 100 the combustible mixture which is deflected by the convexed side of the boss 4. The convertibility of the device is a provision which will allow its use for heating in extreme or 105 moderate temperatures and in many environments. The mobile parts of the device provide means for disposing the retort in various positions relative to the burner member and for prompt and economical installation. The by-products of the retort gravitate the same as the oil and find lodgment 110 at the lower end of the device thereby the retort and burner are always free of dirt and the like.

Having described my invention what I 115 claim is—

1. In a gas generating oil burner, the combination of a base plate provided on its upper side with a vertical flange extending in the form of an ellipse and forming with the 120 plate a basin and centrally of the basin with an up-set boss having its upper side formed convex, an inverted U-shaped pipe mounted on said boss and piercing its convexed side, the arch in the pipe being provided transversely in vertical direction with oppositely disposed registering holes, a retort mounted on the arch of said pipe and having a cored extension penetrating the pipe, and a supply 125 pipe connected with said retort.

2. In a gas generating oil burner, the combination of a base plate provided on its upper side with a vertical flange extending in the form of an ellipse and forming with the plate a basin and centrally of the basin with an up-set boss having its upper side formed convex, an inverted U-shaped pipe mounted 30 on said boss and piercing its convexed side, the arch in the pipe being provided transversely in vertical direction with oppositely disposed registering holes, a housing member movably disposed on said plate within 35 said basin and surrounding said U-shaped pipe, said member comprising an elliptically extending horizontally disposed oval hollow body portion provided on its periphery with a bead having a series of 40 vents for gas and a circular foot portion partially occupied by said boss, a retort mounted 45 on said housing and having a cored extension piercing the latter and penetrating the arch in said pipe, and a supply pipe connected with said retort.
3. In a gas generating oil burner, the combination of a base plate provided on its upper side with a vertical flange extending in the form of an ellipse and forming with the

plate a basin and centrally of the basin with an up-set boss having its upper side formed convex, an inverted U-shaped pipe mounted 30 on said boss and piercing its convexed side, the arch in the pipe being provided transversely in vertical direction with oppositely disposed registering holes, a housing member movably disposed on said plate within 35 said basin and surrounding said U-shaped pipe, said member comprising an elliptically extending horizontally disposed oval hollow body portion provided on its periphery with a bead having a series of 40 vents for gas and a circular foot portion partially occupied by said boss, a retort mounted 45 on said housing and having a cored extension piercing the latter and penetrating the arch in said pipe, and a supply pipe connected with said retort.
